(57) **CLAIM**

The ornamental design for a stuffed toy panda, as shown and described.

DESCRIPTION

FIG. 1 is a front perspective view of a stuffed toy panda according to the present design;

FIG. 2 is a front view of a stuffed toy panda according to the present design;

FIG. 3 is a rear view of a stuffed toy panda according to the present design;

FIG. 4 is a side view of a stuffed toy panda according to the present design;

FIG. 5 is a side view of a stuffed toy panda according to the present design;

FIG. 6 is a top view of a stuffed toy panda according to the present design; and,

FIG. 7 is a bottom view of a stuffed toy panda according to the present design.

Surface shading is indicated to shade FIGS. 1-7 to clearly show the contour of three-dimensional aspects of the present design, and forms a part of the design claimed herein.
